UNITED STATES PATENT OFFICE

2,515,370

HIGH ENERGY IGNITION SYSTEM

Frederick J. Hooven, Dayton, Ohio

Application June 5, 1948, Serial No. 31,368

15 Claims. (Cl. 315—211)

1

This invention relates to ignition systems for internal combustion engines.

The principal object of the invention is to provide an ignition system which is simple and economic in construction and operation and which affords increased energy for the production of the spark.

It is also an object to provide such an ignition system having a single breaker and in which the circuit through the induction coil is allowed to remain closed for a longer period than the interval between successive operations of the breaker thus providing for a substantially greater build-up of the current through the coil with a correspondingly increased spark energy when the breaker opens.

It is a further object to provide an ignition system having a single high tension transformer and a single breaker associated with a plurality of induction coils which are included in the circuit in successive overlapping relation and arranged to have the current therethrough build up for a longer period of time than the interval between operations of the breaker.

It is a still further object to provide such a system in which the current flow through the breaker for each successive operation thereof takes place in the opposite direction thus promoting durability and longer life for the breaker contacts.

It is also an object to provide an ignition system in which the circuit is modified during starting to provide substantially increased energy in the ignition circuit under these conditions.

Other objects and advantages will be apparent from the following description, the accompanying drawings, and the appended claims.

In the drawings:

Fig. 1 is a diagrammatic showing of an ignition system in accordance with the present invention adapted for an 8 cylinder engine.

Fig. 2 is a timing diagram showing the sequence of the various steps or operations in the system of Fig. 1;

Fig. 3 is a diagrammatic showing of an ignition system in which provision is made for increasing the spark energy during the starting of the engine; and

Fig. 4 is a timing diagram showing the sequence of events in connection with a system adapted for a 12 cylinder engine.

In providing high tension spark impulses for the ignition system of an internal combustion engine, a commonly used system includes an induction coil energized from a low voltage di-

2

rect current source, such as a car battery. The timing of the sparks in such a system may be effected by a cam operated contactor or breaker which interrupts the circuit between the primary or low tension side of the coil or transformer and the battery at the instant the spark is desired, and ordinarily re-establishes the circuit as soon thereafter as is mechanically practicable. The rapid change in flux produced by the interruption of the primary current causes the induction of a high voltage in the secondary of the transformer which is utilized to produce a spark in the spark plug of the engine, the spark being directed to the proper plug and cylinder by means of a distributor.

The electrical energy stored in the induction coil at the moment of its release may be expressed as:

$$20 \quad W = \frac{i^2 \times L}{2} \quad (1)$$

where

W is the energy in joules

L the inductance of the coil in henries, and

25 i is the current flowing to the coil winding in amperes.

A resistance R is ordinarily included in the circuit in order to limit the flow of current through the coil to a proper value, depending upon the voltage E of the battery, and the resistance within the coil itself.

When the circuit is established through the coil and battery the flow of current thereafter is expressed by

$$30 \quad i = i_0 \left(1 - e^{-\frac{RT}{L}} \right) \quad (2)$$

where

T is the time in seconds after the circuit is closed,

e is the Napierian log. base and

i₀ is

$$\frac{E}{R}$$

In high speed multi-cylinder engines, the inductance of the coil L is limited to that value at which the current will rise to a working value in the available time when the engine is running at its maximum speed. Assuming an 8 cylinder engine rotating at a crank shaft speed of 4,500 R. P. M. and a cam shaft speed of 2,250 R. P. M., and assuming the duration of the closure of the breaker is 30% of cam shaft rotation, the time T available for the increase of current in the coil

will be approximately .0022 second. On the assumption that a current of

$$\frac{I_0 \frac{i_0}{\sqrt{2}}}{2}$$

giving half the energy of the maximum current will be sufficient at this speed, and further assuming a voltage E of 6 volts, and that $i=6$, $R=1.2$, $i_0=5$, and $i=3.54$, Equation 2 above may then be solved for L , with L equalling .0021.

The maximum spark energy available with such a system will then be

$$\frac{i_0^2 \times L}{2} = .027$$

joule per spark and this only at speeds so low that i is substantially equal to i_0 . At 4,500 R. P. M. such a system will produce only half the maximum energy, or .0135 joule.

In current motor car engines, where multiple cylinders are the rule, engine speeds are high, wide spark plug gaps are usually provided to facilitate smooth running, and battery voltages are usually limited to about 6 volts. Whenever, because of high engine speed or a large number of cylinders, more sparks per second are required then a single coil system will provide, or where by virtue of wide plug gaps or a high compression ratio a larger energy per spark is desired, it is customary to use a double coil system, such as the duplication of the entire ignition system, one part being used for each half of the engine. In addition to materially increased cost, such an arrangement has the disadvantage that it requires synchronization of the two systems to afford uniform timing for the entire engine.

In accordance with the present invention the energy output of a two coil system is provided while retaining the advantage that the entire timing operation of the engine is accomplished by a single breaker so that there is no necessity for synchronizing two separate systems. Further, the arrangement is such that there is a substantial saving in the high tension transformer and distributor commonly used with double coil systems, only a single such transformer being required, and it being of different, and less expensive, construction than that employed in the double coil systems. The circuit arrangement is further such that the single breaker which controls the timing of the spark impulses is arranged so that alternate breaks are of opposite polarity, this feature being favorable to prolonging the life of the contact points. Thus the system provides for more reliable and effective ignition throughout the entire range of normal running of the engine and particularly at the higher speed ranges where a full and adequate spark is maintained.

The invention also provides improved ignition characteristics when the engine is operating at slow speed, and particularly when it is being started. Under these conditions, where the engine is cold, with the battery voltage being low and further depressed by the load taken by the starting motor, or where the spark plug gaps are abnormally wide. These factors, separately or in combination, may result in failure of the engine to provide sufficient sparking voltage at the spark plugs to start. In accordance with the present invention the ignition energy available under such conditions may be substantially increased without increasing the current flow through the breaker and thus without overloading the breaker contacts. With the same current

flow, a substantial increase in spark energy is provided, so that adequate sparking voltages are assured, thus greatly facilitating the starting of the engine. When the engine speeds up, or when the starting operation is terminated, the circuit conditions are restored to their original condition, the system thus providing for increased spark energy at low speed, as well as when operating at high speed.

5 Referring to the drawing, Figs. 1 and 2 illustrate an embodiment of the invention suitable for providing ignition energy for an 8 cylinder engine. The battery is shown at 10, the ignition switch at 11 and the two induction coils 12 and 13, both of which are supplied with energy from the battery. Coils 12 and 13 are connected respectively through current limiting resistors 14 and 15 with cam operated switches shown generally at 20 and 21. These switches include 10 multiple contacts 22 and 23 cooperating respectively with fixed contacts 24 and 25, the latter being connected together and to the opposite side of battery 10 through wire 26. A cam 30 shown as having 4 lobes spaced 90° apart is arranged to actuate the switches 20 and 21, the switches being located in such relation to the cam and to each other that they operate alternately, with an opening movement of each such switch occurring every 45° of revolution of cam 30. It will be understood that cam 30 is driven from a shaft 31 which may be the usual timing shaft of the engine, such as the engine cam shaft, or a shaft operated in direct relation thereto.

20 Cam shaft 31 also carries an 8 lobed cam 35 which is arranged to actuate the breaker 36 shown as having a movable point 37 and a fixed switch point 38. Fixed switch point 38 is shown as connected to the movable contact 22 of the cam operated switch 20 by wire 40 while movable switch point 37 is shown as connected to the movable contact 23 of cam operated switch 21 by means of wire 41. A single condenser 43 is connected across the breaker points 37, 38. The primary or low tension winding 45 of the transformer shown generally at 46 is connected directly across the breaker points 37, 38, in circuit with a suitable current limiting resistor 47. The secondary or high tension winding 48 of the transformer is connected at one side to ground as shown at 49, and its other terminal is connected through the distributor 50 which is mounted on and driven from the cam shaft 31, in order to distribute the high tension spark impulses selectively through distributor points 51 to the proper spark plugs 52, in the usual manner.

60 The switches 20 and 21 are shown as so arranged that they open alternately prior to the opening breaker points 37, 38 and close alternately after the closing of the breaker contacts; the arrangement also is such that switches 20 and 21 are never both open at the same time. The sequence of events and the timing of the system is as shown in the timing diagram of Fig. 2 in which the energization of the respective coils 12 and 13 and the times of closing and remaining closed of the switches 20 and 21, and of breaker 35 is indicated by the presence of a solid arcuate line, the deenergization of the coils or opening of the switch contacts being indicated as occurring at the point where the solid arcuate line ends.

65 In operation, and with the parts in the position shown in Fig. 1, breaker 35 has just opened its contacts 37, 38, and on the timing diagram this position is indicated by the vertical line

marked 0°. The opening of contacts 37, 38 has resulted in breaking the circuit through coil 13, switch contacts 23, 25 having already opened. The circuit through coil 12 is closed through switch contacts 22, 24 but there is no circuit to continue the flow of battery current through coil 13, the only circuit for the discharge of the energy therein being through condenser 43 and the primary 45 of the transformer. Thus the interruption in the circuit results in a surge of current through primary winding 45 of the transformer, producing a high voltage spark in the secondary 48 which is thereupon distributed to the spark plug 52. At the same time, switch 20 being closed, a charging circuit is maintained from battery 10, through switch 11, inductance coil 12, resistor 14, the contacts of switch 20, and through wire 26 to the other side of the battery so that the current is building up in coil 12 notwithstanding the opening of the breaker 35.

In the next interval, shown as occurring at about 15°, breaker 35 recloses its contacts and thereupon a circuit is established for the flow of charging current through coil 13, this circuit being from battery 10, through switch 11, coil 13 and resistor 15, wire 41, contacts 37, 38, wire 40, contacts 22—24 of switch 20, and through wire 36 to the other side of the battery. Thus at this time and for the next interval, a charging current is maintained through both coils 12 and 13.

At a somewhat later interval, shown as at about 25°, switch 21 closes its contacts 23, 25, but this does not produce any change in the circuit since it merely establishes a parallel energizing path for the induction coil 13.

Subsequently, and at approximately 35°, switch 20 opens its contacts 22—24, but this likewise does not produce any change in the circuits, the current continuing to flow through both induction coils 12 and 13, the circuit being maintained through breaker contacts 37 and 38. The circuit for energizing coil 13 is directly through contacts 23, 25, while the circuit for the energizing of coil 12 is through wire 40, breaker contacts 37, 38, wire 41 and contacts 23 and 25. The current is thus allowed to build up over an extended period of time in coil 12, the total interval in the arrangement shown being about 75°.

At a position shown as the 45° point, and after remaining closed for approximately 30°, the breaker 35 opens its contacts 37, 38, thereby abruptly breaking the circuit through coil 12. This produces a heavy surge of current which flows through the primary 45 of the transformer, producing a high energy spark in the same manner as described above, such spark being distributed to the next point 51 of the distributor for delivery to the proper plug 52. The flow of charging current through coil 13 however is not interrupted but continues until the next operation of the breaker.

It will be seen from the foregoing description that both the closing and opening of the circuits through both induction coils 12 and 13 occur at the breaker points 37, 38, and that the circuit is neither closed nor opened at the contacts of switches 20 or 21. These latter switches serve to transfer the circuit and to provide for the alternate action and sequential energization of the two coils in overlapping relation to each other, but are not themselves required to control the flow of the current. Therefore they are subject to only limited wear and burning, and may be of relatively inexpensive construction.

The control of the current is handled entirely

by contacts 37 and 38 of breaker 35, and it will be further evident that with each alternate operation of the breaker, the current is flowing in the opposite direction through its contacts. This is advantageous as avoiding objectionable burning, and further contributes to prolonged life and reliability of operation. With the breaker 35 remaining open for about 15° of rotation and being closed for about 30° of revolution, the charging circuit through each of coils 12 and 13 is nevertheless maintained closed over much longer intervals, approximately of the order of 75°, and a correspondingly longer time and increased build up of current flow in the system is therefore provided.

By connecting transformer 46 across contacts 37, 38 of the breaker, and across condenser 43, the energy of the induction coil circuit is converted to high tension energy in a highly efficient way, and in the same manner as if a high tension winding were placed on the same core as the induction coil itself. By utilizing the transformer 20 in the manner shown, it is possible to convert the energy of each of the two induction coil circuits in sequence, thus requiring only a single high tension winding, which is the most expensive part of the coil. Further, it is possible to utilize less material in this winding than would be required for the high tension winding of an induction coil because it is wound on a magnetic core which is not utilized for energy storage and which may therefore be formed without air gaps.

As a specific example, coils 12 and 13 may each be wound with 250 turns of wire on an open core consisting of a bundle of iron wire $\frac{3}{4}$ inch in diameter and $3\frac{1}{2}$ inches long. Primary winding 45 of the transformer may comprise 50 turns of wire on a closed core, while secondary 48 may contain 6,000 turns wound directly over primary 45. Resistor 47 is chosen so that its resistance, in addition to that of primary 45, is approximately equal to the combined resistance of resistor 14 and coil 12, or that of resistor 15 with coil 13. It is also practicable to embody enough resistance in each of the abovementioned coils by suitable choice of wire size so that resistors 14, 15 and 47 are not required as physically separate components.

By comparison, a secondary or high tension winding wound as a part of coils 12 or 13 would require approximately 30,000 turns of wire to give the same voltage as that provided by high tension winding 48, and in order to obtain the advantages as to prolonged time of charging, two such windings would be required.

Breaker 35 may be of comparable construction with the breakers used with a single coil system, points 37 and 38 being suitably formed of tungsten having diameters of from about .150 to .190 inch and a contact pressure when closed of about 16 to 20 ounces. Condenser 43 is likewise conventional, having a capacity of from .15 to .30 microfarad. Since the contacts of switches 20 and 21 do not interrupt any appreciable flow of current, the contact points 22 to 25 may be of silver or other high conductivity material, requiring a smaller amount of material in the contacts and a lower contact pressure, so that the contactors may be of lighter and cheaper construction. It is also noted that the exact moment of opening and closing of switches 20 and 21 is not critical in the operation of the system so that their adjustment, and the effect of wear in use, do not present serious operating difficulties.

When starting an engine with a starter motor and an ignition coil operated from the same battery, severe conditions often result in a failure to provide adequate sparking voltage and the spark plugs, due to the engine being cold, the battery charge being low, the spark plug gaps being widely separated, or a combination of such conditions. If it is attempted to increase the available ignition energy under such conditions by cutting out a part of the current limiting resistance to increase the current in the induction coil, this results in overloading the breaker contacts and may cause premature failure thereof.

In accordance with the present invention a system is provided for substantially increasing the ignition energy without increase of current under starting conditions by rearranging the circuit to include both induction coils in series for each spark. At low operating speeds adequate time is available for the buildup of current in the system so that the energy may be increased by increasing the value of L in Equation 2 above.

Such an arrangement is shown in Fig. 3 in which parts having similar reference numerals are the same in construction and function as those described in connection with Fig. 1.

In addition, the starting motor is shown at 60 which is operated under the control of the starter switch 61 to cause the cranking of the engine. The closing of the starter switch 61 also closes a circuit from battery 10 through the actuating coil 64 of a relay, causing it to attract its armature carrying switch arms 65 and 66, to shift from the position where they are in contact with switch points 67 and 68 respectively when the relay is deenergized, to the position where they are in contact with switch contacts 69 and 70 respectively when the relay is energized.

Analysis of the circuit will show that when starter switch 61 is open and relay 64 deenergized, the circuit is connected in the manner already described with respect to Fig. 1, with the induction coils being caused to be included in circuit with the transformer alternately in the manner already described. However when the switch 61 is closed and relay 64 energized, a circuit is established from battery 10, switch arm 66, contact 70, contact 67, and from there through coils 13 and 12 in series under the control of breaker 35, the circuit then being completed through wire 72 to resistor 14 and battery 10. A parallel circuit from coil 12 passes through wire 13, switch point 69 and switch arm 65, through resistor 15, and back to the other side of the battery. This arrangement provides for maintaining the same overall resistance in the circuit during the series or starting connection as in the running connection. Thus when connected for sequential operation, resistors 14 and 15 are included respectively in the energizing circuits for induction coils 12 and 13. Assuming for example the resistance of each induction coil 12 and 13 to be R and that of resistors 14 and 15 to be $2R$, then the resistance of each separate coil circuit when connected sequentially, will be $3R$. On starting, the resistance of the coils in series will be $2R$ while that of the resistances 14 and 15 in parallel will be R so that the total resistance in the series starting circuit will become $3R$, and thus comparable or equal to that during the running condition.

The system thus provides for approximately double the energy of the spark during the starting period, but without requiring any materially

greater current flow, or requiring increased current to be handled by the various switch mechanisms.

The system above described provides for buildup of the current in each of the induction coils 12 and 13 for a period of about 75° of cam shaft rotation, where the breaker remains open for only about 15° of cam shaft rotation, such interval being about the minimum period practicable mechanically at high operating speeds. With an 8 cylinder engine, this arrangement thus provides about two and one-half times the time available with a simple single coil system, and therefore provides for a value of L of about two and one-half times as large as with a single coil system providing a comparable increase in the energy for each spark. A further increase in time for the current build-up and corresponding increase in spark energy may be obtained by changing the relationship between the timing of the switches 20 and 21 with respect to breaker 35 to provide for the closing of the respective circuits through coils 12 and 13 through switches 20 and 21, respectively, rather than through the breaker contacts 37, 38. This provides for further reducing the opening time and increasing the time during which the charging current flows through each coil in the circuit.

Such an arrangement is illustrated in the timing diagram in Fig. 4 which is shown by way of example as applied to a 12 cylinder engine. As shown in the arrangement of Fig. 4, the cam 30 is similar except that it has six lobes while cam 35 has 12 lobes. The relationship of the two cams on shaft 31 is shown as such that switches 20 and 21 close respectively about 5° after the opening of breaker 35, thus closing the energizing circuit in each instance at switch 20 or 21, as distinguished from having the circuit closed upon the closing of breaker contacts 37, 38. The breaker itself closes at about 15° and thereafter, at about 20° , switch 21 opens its contacts, preparing for the break in the circuit through induction coil 13 at the next following opening of the breaker which occurs at about the 30° point, the energizing circuits for the two coils being thereafter completed alternately and in overlapping sequential relation to each other, throughout the complete cycle of operation of the system. This provides an additional closure time for each coil, making it possible to have the charging circuit closed through each coil for a total of about 55° of cam shaft revolution, making possible a substantial increase in inductance and a corresponding increase in available spark energy, in comparison with a conventional system.

The invention thus provides a simple and highly advantageous ignition system for internal combustion engines which assures the development of a high energy spark at high speeds, comparable to that obtainable at low speeds, and by means of equipment which is relatively inexpensive and which is readily maintained in operating adjustment and repair. High energy is maintained throughout the normal range of speeds, up to the maximum speed at which the engine will operate, and there is no material reduction or loss of energy as the speed reaches its maximum. Further, the invention assures an increased spark energy during the starting condition, while maintaining the same current flow and thus assuring proper and reliable operation of the entire mechanism throughout all conditions of operation.

While the methods and forms of apparatus herein described constitute preferred embodiment

ments of the invention; it is to be understood that the invention is not limited to these precise methods and forms of apparatus, and that changes may be made therein without departing from the scope of the invention which is defined in the appended claims.

What is claimed is:

1. In an ignition system, the combination of a pair of induction coils, a pair of switches, means connecting said switches in separate circuits through said induction coils with a source of electrical energy, a breaker, means connecting said breaker to both of said switch means, a high voltage transformer having its primary connected across said breaker and its secondary adapted to supply a high voltage ignition circuit, means for operating said switch means alternately to cause energization of said two induction coils at intervals with the intervals of energization for one coil overlapping those for the other, and means for operating said breaker at twice the frequency of said switch means to break the energizing circuit through each of said induction coils at said breaker to provide for energizing the primary of said transformer.

2. In an ignition system adapted to be supplied from a source of electrical energy, the combination of a pair of induction coils, a breaker, a pair of switch means, means for operating said switch means alternately, means connecting said breaker in circuit with each of said induction coils through said switch means to establish an energizing circuit from said source through said induction coils alternately upon each successive closing of said breaker, means for breaking said energizing circuits alternately upon each opening movement of said breaker, and a high tension transformer connected across said breaker for energization thereby upon each opening operation thereof.

3. In an ignition system adapted to be supplied from a source of electrical energy, the combination of a pair of induction coils, a breaker, an energizing circuit for each one of said coils, switch means in said energizing circuits providing for closing said circuits alternately through alternate ones of said coils upon the closing of said breaker, switch means in said circuits providing for alternate opening thereof upon each opening operation of said breaker, and a high tension transformer having its primary connected across said breaker for energization upon each opening of said circuits.

4. In an ignition system adapted to be supplied from a source of electrical energy, the combination of a pair of induction coils, a breaker, an energizing circuit for each one of said coils, switch means in said energizing circuits providing for closing said circuits alternately through alternate ones of said coils upon the closing of said breaker, switch means in said circuits providing for alternate opening thereof upon each opening operation of said breaker with the opening of each one of said circuits following the closing of the other said circuit, and a high tension transformer having its primary connected across said breaker for energization upon each opening of said circuits.

5. In an ignition system, a high voltage transformer having a primary and a secondary, a pair of induction coils, a single breaker in circuit with both said induction coils and with the primary of said transformer, switching means for controlling the energizing circuit for one of said induction coils to establish a flow of current through said breaker in one direction, switching means

for controlling the energizing circuit for the other of said coils to establish a flow of current through said breaker in the opposite direction, and means for breaking the flow of current to each said coil at said single breaker.

5 6. In an ignition system, a high voltage transformer having a primary and a secondary, a pair of induction coils, a single breaker in circuit with both said induction coils and with the primary of said transformer, switching means for controlling the energizing circuit for one of said induction coils to establish a flow of current through said breaker in one direction, switching means for controlling the energizing circuit for the other of said coils to establish a flow of current through said breaker in the opposite direction, means for closing the energizing circuit for one of said coils prior to the opening of the circuit for the other said coil, and means for breaking the flow of current to each said coil at said single breaker.

10 7. An ignition system for use with an internal combustion engine comprising a high tension transformer, a distributor on the high tension side of said transformer, a breaker on the low tension side of said transformer, a plurality of induction coils, switch means for establishing a charging circuit through each of said induction coils in sequence and for maintaining said circuit closed for a period of time greater than the interval of each said operation of said breaker, and means for successively including each of said coils in circuit with said breaker to provide for the breaking of the circuit through said coils and through the low tension side of said transformer sequentially at the same said breaker at each successive operation thereof.

15 8. An ignition system for an internal combustion engine which comprises a high tension transformer, a distributor in the high tension winding of said transformer, a breaker in the low tension winding of said transformer, at least two induction coils, switch means for establishing a circuit through the primary of said transformer and through said induction coils in sequence during normal running of said engine, and controllable means for including said induction coils in series for increasing the energy developed by said transformer during starting.

20 9. In an ignition system system for an internal combustion engine, the combination of a pair of induction coils adapted to be energized from a source of energy, a high tension transformer having a primary and a secondary, a single breaker, means for alternately including each said induction coil in an energizing circuit with said primary providing for greater time of closing of said energizing circuit through each said induction coil than the interval between operations of said breaker, and means for breaking the circuit through each of said coils alternately at successive operations of the same said breaker.

25 10. In an ignition system for an internal combustion engine adapted to be energized from a source of energy, the combination of a plurality of induction coils, a breaker, a high tension transformer, means for establishing a charging circuit through one said induction coils and said transformer, means forming a concurrent charging circuit through the other of said induction coils, means including said breaker for breaking the charging circuit through the first said coil, means providing for maintaining said charging circuit through the other of said induction coils, and means including the same said breaker for

breaking the circuit through said other induction coil in timed relationship with the breaking of said first charging circuit.

11. The method of providing high energy spark ignition in an ignition system of an internal combustion engine which comprises storing electrical energy successively in each of a plurality of induction coils, connecting the coils in sequence with a transformer to develop a high energy surge therethrough and through the coil the circuit of which is broken while maintaining the flow of current through the next successive said coil, transferring the circuit through each of said coils after it has been established in order to maintain such flow of current therethrough for a period longer than the interval between sparks, and breaking the circuit through each of said coils in sequence and in accurately timed intervals at the same point.

12. The method of providing high energy spark ignition in an ignition system for an internal combustion engine which comprises supplying energy to a pair of induction coils in overlapping sequential relation to each other, maintaining the energizing circuit to each said coil for a period longer than the interval between successive sparks, breaking the circuit through said coils alternately and in accurately timed relation at the same point to produce a high energy charge, and supplying said high energy charge to a high tension transformer.

13. The method of providing high energy spark ignition in an ignition system for an internal combustion engine which comprises supplying energy to a pair of induction coils in overlapping sequential relation to each other, breaking the circuit through said coils in alternate relation to produce a high energy charge, supplying said high energy charge to a high tension transformer, and reconnecting the two induction coils in series during the starting of the engine.

14. In an ignition system for an internal combustion engine adapted to be energized from a

source of energy the combination of a pair of induction coils, a breaker, a high tension transformer, switch means for sequentially connecting said induction coils to said energy source in overlapping energizing relation to each other to provide increased time for the build-up of the energy therein, means for including each said coil alternately in circuit with said breaker and with said high tension transformer to produce a high energy surge through said transformer under the control of said breaker, and means for breaking the circuit through each said coil in accurately timed intervals at the same said breaker.

15. In an ignition system for an internal combustion engine adapted to be energized from a source of energy the combination of a pair of induction coils, a breaker, a high tension transformer, switch means for sequentially connecting said induction coils to said energy source in overlapping energizing relation to each other to provide increased time for the build-up of the energy therein, means for including each said coil alternately in circuit with said breaker and with said high tension transformer to produce a high energy surge through said transformer under the control of said breaker, and controllable means for connecting said induction coils in series to provide increased spark energy for starting.
